PORTABLE COMMODE

Morton I. Thomas, Monroe, N.Y., assignor to Temco
Products, Inc., Passaic, N.J.

Filed Apr. 9, 1973, Ser. No. 349,051

Term of patent 14 years

Int. Cl. D23—02

U.S. Cl. D23—48

FIG. 1

FIG. 1 is a perspective view of a portable commode showing my new design; and

FIG. 2 is a rear perspective view thereof.

I claim:

The ornamental design for a portable commode, substantially as shown.
